(74) Attorney, Agent, or Firm—Venable LLP; Robert Kinberg

(21) Appl. No.: **29/179,115**

CLAIM

(22) Filed: **Apr. 7, 2003**

The ornamental design for a rechargeable battery operated candle light, as shown and described.

(51) LOC (7) Cl. **26-03**

DESCRIPTION

(52) U.S. Cl. **D26/104**

FIG. 1 is a perspective view from the front-top side of the rechargeable battery operated candle light showing our new design;

(58) Field of Search D26/93, 96, 104,

FIG. 2 is a front view of the design shown in FIG. 1;

D26/106, 108, 110, 112; 362/410-415,

FIG. 3 is a rear view of the design shown in FIG. 1;

159, 194, 195, 266, 806

FIG. 4 is a left side view of the design shown in FIG. 1;

(56) **References Cited**

FIG. 5 is a right side view of the design shown in FIG. 1;

U.S. PATENT DOCUMENTS

FIG. 6 is a top view of the design shown in FIG. 1; and,

D377,229 S * 1/1997 Shalvi D26/68

FIG. 7 is a bottom view of the design shown in FIG. 1.
